FEEDING DEVICE FOR FOOD CUTTING MACHINES

Hermann Schaumburg, Cassel, Germany

Application December 11, 1933, Serial No. 701,927
In Germany May 26, 1933

1 Claim. (Cl. 146—113)

Food cutting machines are known in which a portion of the gearing actuating the feeding device for the article of food to be cut is situated above the feeding cylinder, whereas the driving mechanism proper is situated below or at the side of the feeding cylinder. If an automatic reverse and disengagement of the drive is provided, this is effected by transmitting elements which represent a danger and prevent the charging of the feeding cylinder.

The invention provides a feeding device for the articles of food to be cut, in which the operation of the automatic reverse and disengagement of the driving mechanism for the feeding piston is effected within the gearing arranged above the feeding cylinder directly by means of the feeding piston or feeding spindle, all the mechanical parts hampering and endangering the service of the feeding cylinder being eliminated.

The shifting of the gear coupling for the return movement of the feeding piston is effected by an arm on the upper end of the feeding spindle, which arm, through the intermediary of a rod, actuates an abutment member, thereby releasing a mechanism locking the coupling. The spring loaded coupling spindle springs back when the abutment member is actuated, causing the claws of the coupling to engage in the return motion wheel of the gearing and the accelerated return movement of the piston. The reverse movement of the machine and consequently the stopping of the feeding piston on reaching its extreme raised position are effected by the feeding piston contacting with a pin which is connected with a double-armed lever effecting the disengagement of the coupling.

The invention is illustrated diagrammatically and by way of example on the accompanying drawing on which Figure 1 is a side-view of a vertical food cutting machine equipped with my improved conveying device, and Figure 2 is a vertical longitudinal section through the driving mechanism of the feeding device, this section being drawn to an enlarged scale.

On the drawing, 1 (Fig. 1) denotes a feeding cylinder receiving the article of food to be cut into pieces, and 2 (Figs. 1 and 2) is a piston which is secured to the lower end of a threaded spindle 4 by means of which the piston can be introduced into said cylinder and exert therein a pressure upon the article of food having prior thereto been placed into said cylinder. That pressure is the feeding pressure by which the piece of food to be cut is pressed against the cutting tool.

The cutting device proper which does not form

a part of this invention and is, therefore, not shown is housed in the casing 7 (Fig. 1), on the top of which the feeding device is arranged. From said casing projects forth laterally an end of the shaft of the cutting device. Said projecting shaft end is provided with a fast and a loose belt pulley 6 and with a cord pulley 38^a connected by a rope 5 with a rope pulley 38 affixed to a horizontal shaft 8 extending into the casing 3 of the feeding device.

On the shaft 8 are two shiftable pairs of cog-wheels, viz. the pair 9, 10 and the pair 11, 12. Parallel to said shaft is arranged a counter-shaft 34 bearing a sleeve 8^a to which are firmly affixed four cog-wheels 13, 14, 15 and 16. The cog-wheel pair 9, 10 is connected with a grooved coupling roll 17^a and the cog-wheel pair 11, 12 is provided with a grooved coupling roll 18^a. The roll 17^a is engaged by a shiftable coupling fork 17 and the roll 18^a is engaged by a shiftable coupling fork 18. The two forks are attached to rods 19 and 20 respectively, which extend through the casing 3 and project forth from it counter to the pulley 38 and are provided at their free ends with grips 19^a and 20^a so that they can be shifted in order to couple either the wheel 9 with the wheel 13 or the wheel 10 with the wheel 14 (in both cases by means of the members 20^a, 20, 17 and 17^a) or the wheel 11 with the wheel 15 or the wheel 12 with the wheel 16 (in both cases by means of the members 19^a, 19, 18 and 18^a). The counter shaft 8^a can, thus, be rotated with four different speeds.

On the shaft 8 is also a cog-wheel 21 and on the shaft 34 is a cog-wheel 23 and between these wheels is a cog-wheel 22. It will be obvious that when rotary motion is transmitted from the shaft 8 to the shaft 34 by the intermediary of said wheels 21, 22 and 23 the shaft 34 will be turned counter to the direction of rotation imparted to it by the wheels 9—16. The wheel 21 is larger than the wheel 23 so that the rotary speed of the shaft 34 will be higher than that of the shaft 8.

The shaft 34 and the sleeve 8^a can be coupled with one another by a coupling member 26 connected with said shaft by feather and groove, and the cog-wheel 23 can be connected with the shaft 34 by another coupling member 26, each coupling member being engaged by coupling pins projecting forth towards one another from said wheels 16 and 23. The two coupling members 26 which completely resemble one another are in engagement with an arm 25 located between them and being affixed to the inner end of a horizontal rod 55

31, the other end of which extends through the right-hand wall of the casing 3 and is there provided with a grip 24 by means of which said rod can be shifted in such a manner that the shaft 5 34 is coupled either with the wheel 16, that is to say, with the sleeve 8^a and all cog-wheels affixed thereto or with the cog-wheel 23, but when the rotary and the shiftable parts of the mechanism are in the position shown in Fig. 2, 10 the shaft 34 is not rotated at all; in other words: the device is at a standstill (except the driving shaft 8).

On the top of the spindle 4 is an arm 27 which contacts with the upper end of a vertical rod 28 when it arrives in its lowermost position, 15 as shown in Fig. 2, in which the main portion of the spindle is broken out. The other spindle portion below the gap is, however, in its uppermost position, as is, consequently, also the piston 2. 20 The rod 28 is guided in the top plate of the casing 3, as well as in an abutment member 39 through which it projects a little with its lower end 37, this end forming an abutment for a projection 36 provided on an oscillable arm 29 subjected to the upwardly directed pressure of a helical compressive spring 29^a. The rod 31 is surrounded with a helical compressive spring 31^a located between said abutment member 39 and an intermediate wall 3^a of the casing 3. By shifting the rod 31 to the left (Fig. 2), the arm 25 will 25 couple the shaft 34 with the sleeve 8^a and this sleeve will be rotated with that speed determined by the cog-wheels chosen. The rotary motion is transmitted to the threaded spindle 4 by means of bevel-wheels 34 and 34^a, of which the latter is internally threaded so as to move the spindle 4 downwardly whereby the piston 2 will be moved into the cylinder 1 shoving the article of food therein contained down to the 30 cutting device located in the casing 1. When the arm 27 of the spindle 4 touches the rod 28, the lower end 37 of the same moves the arm 29 downwardly counter to the pressure of the spring 29^a whereby the projection 36 will be moved away 35 from said end 37 so that the abutment will be released and the spring 31^a will suddenly move the rod 31 to the right, the arm 25 effecting now coupling between the coupling member 26 with the cog-wheel 23, in consequence whereof the 40 wheels 34 and 34^a will be turned counter to the former direction. The spindle 4 and the piston 2 will, therefore, be lifted.

When the piston arrives in its uppermost position, it lifts a pin 35 (Fig. 2) that turns a double-armed lever 32 supported on a pivot 33. The upper arm of this lever acts upon the arm 25 and

this arm shifts the couplings 26 to the left so that the rotary motion of the shaft 34 is no longer transmitted to the bevel-wheels 34 and 34^a. The device comes now to a standstill and another piece of the article of food can be put into the cylinder 1. This having been done, the grip 24 is moved to the left, when another coupling will be established between the members 26 and 16, whereupon the device will again commence to work.

Instead of the simple cord-pulley 38 a stepped pulley may be used so that the number of the different speeds can be still more increased.

I wish it to be understood that I do not limit my claims to the constructional form shown merely by way of example. Many departures in the details are possible without departing from the gist and essence of the invention.

I claim:

A feeding device for the material to be cut on food cutting machines, comprising in combination a feeding cylinder, a piston adapted to vertically reciprocate in said cylinder, a spindle carrying said piston at one end, a driving gearing adapted to operate said spindle, a reversing mechanism 25 for said gearing including a spindle feed wheel, a spindle reverse wheel and a coupling member shiftable between said feed wheel and said reverse wheel, an arm loosely carrying said coupling member, a horizontal push rod carrying said arm and adapted to bring said coupling member into engagement with said spindle feed wheel to effect the feed movement of said piston, means for locking said push rod in pushed in position, a vertical rod resting at one end on said locking means, an arm on the end of said spindle remote from said piston adapted, when said spindle approaches its extreme lower position, to bear against the other end of said vertical rod and press said vertical rod downwards to disengage said locking means, a spring on said horizontal rod adapted to push said horizontal rod outwards and bring said coupling member into engagement with said spindle reverse wheel to effect the return movement of said piston, a 45 double armed lever loosely bearing with one arm against the arm carrying said coupling member, and a vertical pin bearing against the other arm of said double armed lever and adapted to be lifted by said piston as it nears its extreme raised 50 position, to oscillate said double armed lever to bring said coupling member into its intermediate position out of engagement with both of said wheels to interrupt the drive of said spindle and bring said piston to a standstill in raised position.

HERMANN SCHAUMBURG.
